**REFRIGERATOR WITH DEFROST WHEN
NECESSARY SYSTEM**

Robert S. Hanson, Dayton, Ohio, assignor to General Motors Corporation, Detroit, Mich., a corporation of Delaware

Filed Dec. 2, 1965, Ser. No. 511,098
13 Claims. (Cl. 62—156)

ABSTRACT OF THE DISCLOSURE

In preferred form, a refrigerator including above and below freezing compartments, an evaporator compartment, an evaporator coil in the evaporator compartment having an integral fin and tube configuration wound to present an increased cross-sectional flow area through the center of the evaporator compartment to prevent undesirable reduction of air flow through the compartment following frost build-up on the evaporator coil and including a defrost when necessary control having a first power diaphragm responsive to the skin temperature of the evaporator coil and the temperature of an interior part of the compartment and further having a second power diaphragm responsive to ambient conditions about the refrigerator for modulating the control action in accordance with ambient temperature variations.

This invention relates to frost-proof refrigerators and more particularly to an improved evaporator assembly for cooling air being circulated in frost-proof refrigerators.

Frost-proof refrigerators generally are characterized by a primary air circulation system that includes an evaporator enclosure forming an evaporator compartment separate from the above and/or below-freezing compartments through which the primary air stream is circulated. The recirculated primary air stream draws moist air from the respective freezing compartments across an evaporator located within the evaporator compartment and the moisture in the recirculated air is deposited as frost on the evaporator member so as to be removed from the air stream. By virtue of this type of system, there is little or no frost buildup in the primary food storage compartments of a refrigerator or the like that requires periodic removal by the housewife.

While frost-proof refrigerators solve the problem of frost buildup in the food storage compartments and especially in the below-freezing compartment of a refrigerator, it is necessary to include a provision in such systems to defrost the evaporator when it becomes coated with a frost buildup that will reduce the desired air flow pattern for cooling in the freezing compartments of the refrigerator or a frost buildup that will reduce the cooling effectiveness of the evaporator.

In the past, the primary air flow was passed through or across evaporator members that have been characterized as having rather a substantial number of separate fins directed across the air flow passageway. In order to provide a sufficient heat transfer surface between the evaporator and the recirculated air, the number of fins necessarily has been relatively substantial and the spacing between the fins has been of a relatively reduced nature to provide sufficient fin surface on the evaporator member.

One problem in such frost-proof systems has been to maintain a desired air flow across the evaporator in the evaporator compartment as frost is deposited thereon and, furthermore, to remove periodically the frost built up on the evaporator section when the frost buildup reduces the cooling effectiveness of the evaporator member.

Accordingly, an object of the present invention is to improve frost-proof refrigerators by the provision therein

2

of an improved evaporator arrangement for cooling the primary air cooling stream through the frost-proof refrigerator by the provision of a three-piece evaporator including a helically wound integral fin and tube member that forms an opened central region through the evaporator for the uninterrupted passage of air therethrough and wherein infrared heater means are located within the opened passageway through the helically wound integral fin and tube for removing frost therefrom by radiant heat transfer from said heating means rather than conduction through said evaporator.

A still further object of the present invention is to improve frost-proof refrigerators having a primary air circulating system including refrigerant means for cooling the air stream by the provision of an improved evaporator arrangement including a helically wound integral fin and tube member having a central opened region therethrough defined by a plurality of fins directed interiorly of said coil with end portions thereon located in spaced apart relationship with one another through a distance in excess of the length of the fins whereby the primary air circulation can pass through said evaporator following a frost buildup on the fins.

Still another object of the present invention is to improve frost-proof refrigerators having above and below-freezing compartments and means for circulating a cold air stream through said compartments by the provision of an improved evaporator arrangement for cooling the circulating air and removing moisture therefrom including

a helically coiled integral fin and tube evaporator member having a first plurality of passes located in a common plane and a second plurality of passes located in a common plane spaced apart from that of the first plurality of passes and wherein the plurality of passes each includes a large number of integral fins directed interiorly of the helical coil to form an open space having a width equal to that of the passes and a depth greater than the length of the fins to direct the circulating primary air stream through the helically coiled evaporator member in good heat transfer relationship with all portions thereof irrespective of a frost buildup on the fins thereof.

A further object of the invention is to improve a frost-proof refrigeration system of the type set forth in the preceding object wherein the helically coiled evaporator member includes side wall members for forming open spaces within an evaporator compartment on either side of the helical coil and wherein means are included to direct air through said side walls interiorly of said coil downstream of the inlet end of said coil to improve the distribution of frost on said coil.

A still further object of the present invention is to improve frost-proof refrigerators of the type including a primary cold air circulation system for passing moist air in heat transfer relationship with an evaporator for cooling the air stream and removing frost therefrom by the provision of an automatic defrosting system including infrared heating means for removing frost from the evaporator by direct radiant transfer to the evaporator wherein the heating means includes an electrically energizable high-temperature resistance element selectively connected across a power source by thermally responsive switch means including a diaphragm actuator associated with a thermally responsive bulb element including a first portion located in direct heat transfer relationship with the coldest portion of the evaporator member and a second portion located in heat transfer relationship with inlet air to the evaporator member whereby when the first bulb portion senses a first predetermined temperature, a defrost cycle is initiated, and when the second bulb portion senses a second predetermined temperature, the defrost cycle is automatically terminated.

Yet another object of the present invention is to improve defrost systems of the type set forth in the preceding object by the provision of a helically coiled integral fin and tube evaporator member having a plurality of fins directed interiorly of the coil and located in spaced relationship from one another to form an open space centrally of and through the coil in which said infrared heating means is located.

Further objects and advantages of the present invention will be apparent from the following description, reference being had to the accompanying drawings wherein a preferred embodiment of the present invention is clearly shown.

In the drawings:

FIGURE 1 is a fragmentary view in vertical section of the improved evaporator arrangement shown in association with a plural compartment frost-proof refrigerator and a diagrammatically illustrated refrigerant system;

FIGURE 2 is an enlarged view in horizontal section taken through the improved evaporator arrangement;

FIGURE 3 is a view, partially in section and partially in front elevation, of the improved evaporator arrangement;

FIGURE 4 is an enlarged view in vertical section of a portion of an infrared energy source in the improved arrangement;

FIGURE 5 is an enlarged view in vertical section taken along the line 5—5 of FIGURE 3; and

FIGURE 6 is a diagrammatic showing of a control system for the present invention.

Referring now to FIGURE 1, a frost-proof refrigerator 10 is illustrated including an outer cabinet 12 and an inner liner 14 having a layer of thermal insulation 16 therebetween. The inner liner 14 is traversed by an insulated divider partition 18 that forms an above-freezing food storage compartment 20 and a below-freezing food storage compartment 22 within the inner liner 14. Access openings 23, 24 are provided in the inner liner 14 to the compartments 20, 22, respectively. In the illustrated arrangement, the opening 23 is closed by a vertically hinged bottom door 25 and the opening 24 is closed by a vertically hinged top door 26.

Forwardly of the rear wall of the inner liner 14 is located a rear baffle or shroud 27 in which is located a primary air circulating centrifugal fan 28 driven by a motor 30 located within the insulation 16 of the rear wall of the refrigerator 10. The fan 28 directs air through a passageway 32 formed by the shroud 27 and the rear wall of the liner 14 interiorly of the freezer compartment 22 and through a passageway 34 formed by a lower portion of the shroud 27 and the rear wall of the liner 14 into the above-freezing compartment 20. The passageway 34 has a damper 36 located therein that is pivotally supported on the baffle 27 for manual adjustment to proportion the air flow through the passageways 32, 34, respectively, depending upon the amount of cooling desired in the above-freezing compartment 20.

Within the below-freezing compartment 22 is located a bottom freezer panel 38 that forms an evaporator compartment 40 in cooperation with a downwardly bent portion of the insulated partition panel 18. Across the front edge of the panel 38 is located an air return member having a plurality of openings 42 therein for returning circulated air from the below-freezing compartment 22 interiorly of the evaporator compartment 40 and the divider partition 18 has a plurality of openings 44 therein to direct return air from the above-freezing compartment 20 into the evaporator compartment 40. The panel 38 in cooperation with the rearwardly located shroud 27 forms an inlet opening 46 to the recirculating fan 28 which draws return air from the openings 42, 44 through the evaporator compartment 40 to be discharged through the discharged passageways 32, 34, respectively.

The above-described recirculating primary air stream is cooled by an improved evaporator arrangement 48

within the evaporator compartment 40 that has a refrigerant accumulator 47 connected by a conduit 49 to the suction side of a refrigerant compressor 50 that directs compressed refrigerant through a condenser 51 thence through a suitable refrigerant expansion means representatively shown as being an expansion valve 52, thence through a conduit 54 connected to the inlet end of the evaporator 48.

More particularly, and as best seen in FIGURES 2, 3 and 5, the improved evaporator 48 is of a low-cost, three-piece construction including a helically coiled integral fin and tube evaporator member 56 having a first plurality of lower passes 58 located in a common plane adjacent a drip pan 55 supported on the insulated divider partition 18 under the member 56 to collect water defrosted therefrom. Member 56 also includes a second plurality of passes 60 located in a common plane closely adjacent the panel 38. The lower and upper passes 58, 60 are joined by return bend portions 62. Each of the passes 58, 60 includes a plurality of integral fins 64 directed outwardly of the coiled member 56 having the ends thereof spaced apart from the drip pan 55 and the panel 38, respectively. Each of the return bends 62 includes a plurality of radially outwardly directed fins 66 on the outer radius thereof and a plurality of collapsed fins 68 on the inner radius thereof that prevent undesirable bending of the return bend portions 62.

Furthermore, the lower and upper reaches 58, 60 each includes a plurality of integral fins 70 thereon directed 30 interiorly of the coiled member 56 and having their ends spaced apart to form a central opening 72 from the end of the coiled member 56 located immediately downstream of the return openings 42, 44 into the evaporator compartment 40 and the end of the coiled member 56 that is 35 located immediately upstream of the inlet opening 46 to the recirculating fan 28.

The evaporator arrangement 48 further includes spaced apart side members 74, 76 each having a generally U-shaped configuration and edge portions thereof that engage, respectively, the panel 38 in the below-freezing compartment 22 and the upper surface of the drip pan 55. As best seen in FIGURE 5, each of the side members 74, 76 includes a plurality of spaced apart openings 78 in which are located one of the return bend portions 62 40 whereby the coiled member 56 is located within the evaporator compartment 40 with the outer fins 64 thereon spaced as mentioned above and the central opening 72 through the coiled member 56 being located generally centrally of the evaporator compartment 40 in serial 45 air flow relationship with the return openings 42, 44 and the inlet opening 46 to the recirculating fan 28.

As best seen in FIGURE 2, each of the side members 74, 76 are spaced inwardly of the inner liner 14 on the side walls of the refrigerator 10 to form therewith passageways 80, 82 on either side of the coiled evaporator member 56, a block of insulating material 84 is located between the inner liner 14 on one side of the coiled member 56 and the end of the side member 74 located closest to the inlet opening 46 to prevent air flow through the 55 passageway 80 from the return openings 42, 44 and the inlet 46 to the recirculating fan 28. Likewise, a block of insulating material 86 is located between the liner 14 on the opposite side wall and the like end of the side member 76 to prevent direct air flow from the return openings 60 42, 44 and inlet 46 of the fan 28 through passageway 82.

Each of the side members 74, 76, however, includes openings 88 between the return bend portions 62 supported therein that will direct air through the sides of the helically coiled evaporator member 56 into the interior space 72 thereof.

By virtue of the above illustrated arrangement, when the circulating fan 28 is running, air will be discharged into the freezing compartments 20, 22, respectively, where moisture is picked up so as to prevent an undesirable frost buildup in the compartments and especially in

the below-freezing compartment 22. The moist air is returned through openings 42, 44 into the evaporator compartment 40 and distributed through a first path directly into the central opening 72 and the upper and lower spaces between the helical coil 56 and the panel 38 and drip pan 55 to pass serially across the helically coiled evaporator member 56 into the inlet opening of the fan 28.

By virtue of the above illustrated arrangement, namely the provision of a helically coiled integral fin and tube member of the type set forth above, the air flow between the return openings 42, 44 and the fan inlet opening 46 will pass through a substantial open area in which no fins are located. As a result, as frost builds up on the fins, there will be a tendency to prolong the period during which time air will freely pass through the evaporator member before being undesirably restricted by the frost buildup so as to reduce the air flow through the freezing compartments to a degree where the desired temperature levels therein will be reduced in an undesirable fashion.

In addition to the relative open configuration of the helically coiled integral fin and tube member 56, the evaporator assembly 48 is further characterized by the inclusion therein of an improved infrared energy heater assembly 90 that includes an open ended tubular enclosure 92 of a suitable infrared transmissive material, such as quartz, which has opposite end portions thereon directed respectively through an opening 94 intermediate the ends of each of the side members 74, 76. The tubular enclosure 92 has a high-temperature electrical resistance element 96 directed therethrough having the opposite ends connected to a male terminal member 98 that is received within a female terminal 100 having a lead line 102 connected thereto. A tubular cap 104 fits over each open end of the tubular member 92 and the terminal 100, as best seen in FIGURE 4, to prevent the entrance of moisture into the interior of the tubular member 92. An opening 105 in the cap 104 vents the interior of enclosure 92.

The heater assembly 90 is located in the central open space 72 through the helical coil 56 and is disposed slightly forwardly of the coil 56 in the illustrated arrangement to be located in direct radiant heat transfer relationship with most of the fins on the forwardly located passes 58, 60 of the coiled member 56 for removing frost buildup therefrom when the heater assembly is energized. Since the helically coiled member 56 has a relatively open configuration between the fin portions thereof, the energy output from the infrared heater assembly 90 is able, through direct radiant heat transfer, to remove most of the frost buildup therefrom in a highly efficient manner.

The system of defrosting by infrared energy is generally known but in the illustrated arrangement, the combination of the single tubular formed heating assembly and the helically coiled member 56 is characterized by the fact that a relatively opened air flow path is maintained in the evaporator compartment which is desirable in a frost-proof refrigerator for the reasons set forth above and, furthermore, affords an open path between the heater assembly 90 and the fins thereon for direct radiant defrosting.

In accordance with certain other principles of the present invention, the heater assembly 90 is periodically energized by automatic control means to initiate a defrost cycle that is operated without the need for timers, frost detectors or other mechanical devices. The system is economical in construction and utilizes a combination of the temperature of the coldest portion of the evaporator coil, represented in the illustrated arrangement by the accumulator 47, and a means for sensing the temperature of the return air from the food storage compartments.

More particularly, in FIGURE 6 the improved control arrangement is illustrated as including a double-throw, single-pole switch 106 that is electrically connected at one end thereof to a wire L₁ of a suitable power source. The switch 106 is operatively positioned by a first bellows

assembly 108 that is fluidly connected to a capillary tube 110 including a thermally responsive fluid. The capillary tube 110 has a first coil portion 112 thereof located in the return air flow from the above and below-freezing compartments 20, 22, as best seen in FIGURE 2. The capillary tube 110 further includes a second coil portion 114 that is serially arranged with the first portion 112 and located in direct heat transfer contact with the outer surface of the accumulator 47, as best seen in FIGURE 2, which, in the illustrated system, represents the coldest region on the evaporator coil 56.

The switch 106 is further operatively positioned by a second bellows 116 that is in communication with a thermally responsive fluid filled capillary tube 118 that has a bulb portion 120 located in a suitable region of the refrigerator for sensing ambient temperatures in which the refrigerator operates.

A contact 122 of the switch 106 during a cooling cycle of operation of the refrigerator is positioned in electrical contact with a contact 124 that is electrically connected to a conductor 126 which connects a motor 128 for driving the compressor to wire L₂ of the power source. A fan motor 129 is connected in parallel across motor 128 to be simultaneously energized. During a defrost cycle of operation, the switch 106 is moved so that the contact 122 thereof electrically connects to a contact 130 which is electrically connected to one of the terminals 102 from the high-temperature resistance element 96 that has the opposite end thereof electrically connected to the wire L₂.

The switch 106 thus can be characterized as one that will automatically interrupt the refrigeration cycle and start a heating or defrost cycle in response to thermal conditions within the evaporator compartment 42. It is recognized that when an evaporator coil becomes covered with frost, as in the case of an evaporator portion in a frost-proof refrigerator, the amount of heat transferred to the refrigerant in the coil in a given period of time will be reduced. Since the condenser and compressor have a reduced heat load, the back pressure in the system will be reduced and also the temperature of the refrigerant coil 56 will be lowered. It is also recognized that the reduction in the back pressure and the evaporator coil skin temperature under reduced loads, as occurs upon frosting up of the coil, is dependent in part upon the ambient conditions in which the refrigerator is being operated.

In addition to the reduced heat load produced by a frost buildup, in single evaporator frost-proof refrigerators of the type under discussion, as the air passageways through the evaporator become blocked with frost, there is a consequent reduction in air flow and, therefore, a lesser heat transfer to the refrigerant coil than is normally the case. The combination of the reduction of heat transfer produced by frost buildup and that produced by a reduction in air flow will produce a substantial reduction in the skin temperature of the accumulator 47 which will cause the thermally responsive fluid in the capillary tube 110 to condense whereby the bellows 108 will position the contact 122 to complete the energization circuit of the heater 96. When this occurs, the energization circuit for the compressor motor 128 is terminated. Radiant energy from the heater assembly 90, whether by direct radiation heat transfer or by reflective heat transfer off the panel 38 of the freezer compartment 22 and the drip pan 55, will be directed against the frost build up on the fins 64, 70 of the helical coil 56 to cause it to melt and flow into the drip pan 55 for removal through a suitable drain tube (not shown). During the defrost cycle of operation, the centrifugal fan 28 is de-energized to prevent an undesirable transfer of heated air into the compartments 20, 22.

In order to assure that the defrost cycle will be of a sufficient duration to remove the frost buildup on the coil 56, the controller includes the coil portion 112 in the capillary tube 110 at a point in the evaporator compartment 42 which has the temperature thereof increased

at a lesser rate than does the temperature increase in the coil 56 and accumulator 47. Thus the coil portion 112 can be characterized as a defrost terminating bulb which is heated more slowly than the coil 114 to produce a predetermined lag in the opening movement of the contact 122 from the contact 130. When a predetermined temperature is attained, the switch 106 will be positioned by the bellows 108 to open the energization circuit for resistance 96 and to complete the energization circuit for the compressor motor 128 to start a new refrigeration cycle.

The ambient compensating bellows 116 will bias the switch 106 so that the defrost cycle will be initiated at varying accumulator skin temperatures in accordance with the ambient temperature under which the refrigerator is operating. For example, in the illustrated arrangement, the switch 106 will initiate a defrost cycle under 110° F. ambient conditions when the evaporator coil reaches -12° F. Under 90° ambient conditions, the defrost cycle is initiated at an evaporator or accumulator skin temperature of -16° F. and at ambient conditions of 70° F., the defrost cycle is initiated when the bulb 114 senses skin temperature in the neighborhood of -20° F. The ambient compensation enables the automatic defrost system to remove frost from the coil in an effective fashion through a wide range of operating conditions. Without such ambient compensation, the automatic defrosting arrangement illustrated might initiate a defrost cycle before the frost buildup on the coil 56 occurs that needs defrosting.

While the embodiment of the present invention as herein disclosed constitutes a preferred form, it is to be understood that other forms might be adopted.

What is claimed is as follows:

1. A frost-proof refrigerator comprising insulating means forming a below-freezing compartment and an above-freezing compartment, enclosure means forming an evaporator compartment separated from said freezing compartments including an inlet opening and an outlet opening, means for circulating air from said below and above-freezing compartments through said inlet of said evaporator compartment thence through the outlet of said evaporator compartment, said fluid circulating means including a recirculating fan having its inlet in communication with the outlet of said evaporator compartment, a helically coiled integral fin and tube evaporator member located in said evaporator compartment between the inlet and outlet ends thereof, said helically coiled evaporator member including a first plurality of passes located in close spaced relationship with one surface of said evaporator enclosure means and a second plurality of passes located in close spaced relationship with another surface of said evaporator enclosure means, a plurality of return bend portions for joining said first and second plurality of passes and locating said passes apart from one another to form a relatively open air passageway therebetween, said plurality of passes each including a plurality of integral fins thereon directed interiorly of said evaporator member into said air passageway to partially intersect the passage of air between said inlet and said outlet of said evaporator compartment, said passageway through said helically coiled member communicating directly with the inlet end of said evaporator compartment for receiving return air from said above and below-freezing compartments, and means within said evaporator compartment for directing a predetermined portion of the return air from said above and below-freezing compartments interiorly of said helically coiled integral fin and tube evaporator member through the sides thereof for improving the pattern of frost deposition on said evaporator member during the operation of the refrigerator.

2. A frost-proof refrigerator including insulating means forming a below-freezing compartment and an above-freezing compartment, enclosure means forming an evap-

orator compartment separated from said compartments including an inlet opening and an outlet opening, means for circulating air from said below and above-freezing compartments through the inlet of said evaporator compartment thence through the outlet thereof including a recirculating fan having an inlet opening in communication with the outlet opening of said evaporator compartment, means for cooling air passing through said evaporator compartment including a helically formed integral fin and tube evaporator member having spaced apart passes directed substantially across the width of said evaporator compartment, return bend portions for joining said spaced apart passes of said helical coil, said spaced apart passes of said helical coil having a plurality of integral fins formed thereon directed interiorly of said coil and located in spaced apart relationship with one another to form an uninterrupted fluid flow passageway between said inlet of said evaporator compartment and the outlet thereof for free fluid flow of returned air from said above and below-freezing compartments following the deposition of frost on said fins on said passes, and defrost means including a sheathed infrared emissive resistance element within said helically coiled evaporator member for removing frost from said integral fins through direct radiant heat transfer.

3. In the combination of claim 2, said defrost means including means for selectively controlling the energization of said resistance element including a thermally responsive switch having a pair of contacts, a first bellows 30 for opening and closing said contacts, said bellows communicating with a first thermally responsive bulb means including a first portion located in heat transfer relationship with said evaporator for initiating a defrost cycle of operation and a second portion thereof located in heat 35 transfer relationship with the return air from said above and below-freezing compartments for terminating the defrost cycle of operation, a second bellows for modulating opening and closing of said contacts, second thermally responsive bulb means communicating with said second 40 bellows and located in heat transfer relationship with an ambient temperature source for continually modulating the controlling action of said first bellows in response to ambient temperature conditions.

4. In the combination of claim 2, means within said 45 evaporator compartment for directing a predetermined portion of the return air from said above-freezing and below-freezing compartments interiorly of said helically coiled evaporator member downstream of the point where said uninterrupted fluid flow passageway through said 50 helically coiled evaporator member directly communicates with said inlet end of said evaporator compartment.

5. In the combination of claim 4, said means for directing return air through said helically coiled evaporator member including a pair of spaced apart side wall members supporting said helically coiled evaporator member within said evaporator compartment on either side thereof, means forming openings in said side wall members in direct communication with the interior of said helically coiled evaporator member, and means within said evaporator compartment for blocking fluid flow therearound other than through the passageway therethrough and said side member openings.

6. In a frost-proof refrigerator the combination of, 65 insulating means forming a below-freezing compartment and an above-freezing compartment, enclosure means forming an evaporator compartment separated from said freezing compartments, means forming an inlet to said evaporator compartment and an outlet from said evaporator compartment, means for circulating air from said 70 below and above-freezing compartments through said evaporator inlet and said evaporator outlet including a recirculating fan having an inlet opening in direct communication with said outlet opening of said evaporator compartment, means for cooling air circulated through 75 said evaporator compartment including a helically coiled

integral fin and tube evaporator member having an open central region formed by inwardly directed fins on said evaporator member, said central open region directly communicating with said inlet of said evaporator compartment and the outlet of said evaporator compartment, said open region being bounded on either side thereof by spaced apart side walls for supporting said helically coiled evaporator member within said evaporator compartment, said side walls extending across said enclosure means and defining therewith passageway means on either side of said helically coiled evaporator member within said evaporator compartment, means forming openings in said side walls for communicating said side flow passageways with the interior of said helically coiled evaporator member downstream of the portion of the central open region of said helical coil that directly communicates with said inlet opening of said evaporator enclosure, fluid flow through said openings in said side members serving to improve the distribution of frost on said helically coiled evaporator member to prevent undesirable blocking of return air from above and below-freezing compartments directly into the central region of said helically coiled evaporator member from the inlet opening in said evaporator compartment, an elongated tubular member of infrared transmissive material directed through the central region of said helically coiled evaporator downstream of the portion thereof directly communicating with the inlet of said evaporator compartment, a high-temperature resistance element directed through said sheath of infrared transmissive material, means for sealing the interior of said tubular sheath, means for selectively energizing said resistance element for producing infrared radiation therefrom for removing frost from said helically coiled evaporator through direct radiant energy transfer from said infrared emissive element.

7. In the combination of claim 6, said means for selectively controlling the energization of said resistance element including a thermally responsive switch having a pair of contacts, a first bellows for opening and closing said contacts, said bellows communicating with first thermally responsive bulb means including a first portion located in heat transfer relationship with said evaporator for initiating a defrost cycle of operation and a second portion thereof located in heat transfer relationship with the return air from said above and below-freezing compartments for terminating the defrost cycle of operation, a second bellows for modulating opening and closing of said contacts, second thermally responsive bulb means communicating with said second bellows and located in heat transfer relationship with an ambient temperature source for continually modulating the controlling action of said first bellows in response to ambient temperature conditions.

8. In a frost-proof refrigerator, the combination of, insulation means for forming an above-freezing compartment and a below-freezing compartment, said insulating means including a horizontal divider panel between said freezing compartments, a plate located within said below-freezing compartment and extending across the width thereof to form in cooperation with said divider panel an evaporator compartment, means for forming an inlet from said freezing compartments into said evaporator compartment, means for drawing air from said evaporator compartment and for distributing said air into said above- and below-freezing compartments, a helically coiled integral fin and tube evaporator member located within said evaporator compartment having a first plurality of lower passes and a second plurality of passes located above said lower passes within said evaporator compartment, return bend portions for joining said upper and lower passes, said passes having a plurality of integral fins thereon directed outwardly of said helical coil into close spaced relationship with said plate and said divider panel, support members on each side of said helically coiled evaporator member supportingly receiving said return bend por-

tions for locating said helically coiled evaporator member within said evaporator compartment and to locate said outwardly directed fin portions in close spaced relationship with said upper panel and divider panel respectively, said passes each including a plurality of integral fins directed inwardly of said helically coiled evaporator member, each of said inwardly directed fins having inner end portions located in spaced relationship with one another to form a central opening through said helical coil for the free passage of air between said inlet and outlet of said evaporator compartment irrespective of frost buildup on said evaporator member.

9. In the combination of claim 8, said upper plate being of infrared reflective material, a layer of infrared reflective material on said divider panel, a tubular member of infrared transmissive material directed through the interior of said helically coiled evaporator member having the opposite ends thereof supportingly received by said side members, a high-temperature resistance element located within said tubular member, means for sealing the ends of said tubular member against the entrance of moisture interiorly thereof, and means for energizing said high-temperature resistance element into the infrared emissive range, said sheathed element being located in direct radiant heat transfer relationship with substantially all of said inwardly directed fins on said helical coil for removing frost buildup therefrom by radiant heat transfer.

10. In the combination of claim 8, means including said side members for forming opened spaces on either side of said helically coiled integral fin and tube evaporator member, means forming openings in said side members for communicating said side spaces with the interior of said helically coiled member for receiving a predetermined portion of air passing through said inlet of said evaporator compartment for improving the distribution of frost buildup on said evaporator member.

11. In an automatic defrost system for a frost-proof refrigerator, the combination of, means forming an evaporator enclosure having an inlet and an outlet, an evaporator coil located within said compartment, means for directing refrigerant through said evaporator coil, electrically energizable infrared heater means located within said evaporator coil in an opened central region formed therethrough between said inlet and said outlet of said evaporator compartment, means circulating air through said evaporator compartment, said evaporator coil serving to remove moisture from said circulated air, a refrigerant accumulator connected to the outlet of said evaporator coil, means for automatically energizing said infrared heater means for removing frost from said evaporator coil by direct radiant heat transfer thereto, said circuit means including a thermally responsive switch for connecting said infrared heating means across a power source, said thermally responsive switch including bellow means, a thermally responsive fluid containing bulb having a first portion thereof in direct heat transfer relationship with said accumulator and a second portion thereof in heat transfer relationship with air passing through said inlet of said evaporator compartment, said bellow means responding to a predetermined temperature sensed by said first bulb portion to condition said switch to initiate a defrost cycle of operation, said bellows means responding to a predetermined sensed temperature of said second bulb portion to terminate energization of said infrared heating means when said second bulb portion senses a predetermined temperature of air in said evaporator compartment.

12. In an automatic defrost system for a frost-proof refrigerator, the combination of, means forming an evaporator enclosure having an inlet and an outlet, an evaporator coil located within said compartment, means for directing refrigerant through said evaporator coil, electrically energizable infrared heater means located within said evaporator coil in an opened central region formed therethrough between said inlet and said outlet of said

evaporator compartment, means circulating air through said evaporator compartment, said evaporator coil serving to remove moisture from said circulated air, a refrigerant accumulator connected to the outlet of said evaporator coil, means for automatically energizing said infrared heater means for removing frost from said evaporator coil by direct radiant heat transfer thereto, said circuit means including a thermally responsive switch for connecting said infrared heating means across a power source, said thermally responsive switch including bellow means, a thermally responsive fluid containing bulb having a first portion thereof in direct heat transfer relationship with said accumulator and a second portion thereof in heat transfer relationship with air passing through said inlet of said evaporator compartment, said bellow means responding to a predetermined temperature sensed by said first bulb portion to condition said switch to initiate a defrost cycle of operation, said bellow means responding to a predetermined sensed temperature of said second bulb portion to terminate energization of said infrared heating means when said second bulb portion senses a predetermined temperature of air in said evaporator compartment, thermally responsive means for sensing ambient temperature and including means for controlling said thermally responsive switch to delay defrost initiation upon a reduction in ambient temperature.

13. An improved evaporator assembly for association with a frost-proof refrigerator comprising, enclosure means forming an evaporator compartment having an inlet opening and an outlet opening, an evaporator member disposed within said evaporator compartment, said evaporator member including a first and a second plurality of passes located in spaced apart relationship with one another, said first plurality of passes being located in a

common plane, said second plurality of passes being located in a common plane, said first and second plurality of passes being joined by return bend portions, each of said passes having a plurality of fins thereon directed 5 interiorly of said passes and having end portions thereon spaced apart from one another to form a central opening through the center of said passes between said inlet and outlet in said enclosure means, and means within said 10 evaporator compartment for directing air from said enclosure means inlet through said central opening, infrared heater means located interiorly of said evaporator member, circuit means for selectively energizing said infrared heater means for defrosting said evaporator member, said circuit means including a thermostatically operated switch for selectively connecting said infrared heater means across a power source, said thermally responsive means including a first bulb portion located in direct heat transfer relationship with said evaporator member and a second serially connected bulb portion located 15 in heat transfer relationship with air passing through said evaporator compartment inlet, said first bulb portion serving to initiate a defrost cycle of operation and said second bulb portion serving to terminate the defrost cycle of operation.
